[57] CLAIM

The ornamental design for a sanitary countertop machine for storing and dispensing particulate ice, substantially as shown and described.

DESCRIPTION

FIG. 1 is a perspective view looking downward at the front, left side, and top of a sanitary countertop machine for storing and dispensing particulate ice, showing my new design;

FIG. 2 is a front elevational view thereof;

FIG. 3 is a side elevational view of the right side thereof, the left side elevational view being the mirror image of the right side elevational view;

FIG. 4 is a rear elevational view;

FIG. 5 is a top plan view;

FIG. 6 is a fragmentary sectional view taken on line VI—VI of FIG. 3 in the direction indicated by the arrows; and

FIG. 7 is a fragmentary sectional view taken on line VII—VII of FIG. 3 in the direction indicated by the arrows.

The bottom is substantially planar and unornamented.
